(57) **CLAIM**

The ornamental design for blender blades, as shown and described.

DESCRIPTION

FIG. 1 is a top perspective view of blender blades showing my new design;

FIG. 2 is a bottom perspective view thereof;

FIG. 3 is a front elevational view thereof, the rear being the same;

FIG. 4 is a side elevational view thereof, the opposite side being the same;

FIG. 5 is a bottom plan view thereof; and,

FIG. 6 is a top plan view.

In all the views, the broken lines depict environment which forms no part of the design.
